UNITED STATES PATENT OFFICE.

WILLIAM C. BECKWITH, OF CHICAGO, ILLINOIS.

DESIGN FOR A PHONOGRAPH-CABINET.

55,405.

Specification for Design.

Patented June 8, 1920.

Application filed January 12, 1920. Serial No. 351,061. Term of patent 14 years.

To all whom it may concern:

Be it known that I, WILLIAM C. BECKWITH, a citizen of the United States, residing at No. 21 East Austin avenue, at the city of Chicago, in the county of Cook and State of Illinois, have invented a new, original, and ornamental Design for Phonograph-Cabinets, of which the following is a specification, reference being had to the accompanying drawing, forming a part thereof.

The figure is a perspective view of a phonograph cabinet, showing my design.

I claim:—

The ornamental design for a phonograph cabinet as shown.

WILLIAM C. BECKWITH.
